UNITED STATES PATENT OFFICE.

THEODORE R. TREIBER, OF CHICAGO, ILLINOIS, ASSIGNOR TO WILLIAM H. McWHORTER, OF CHICAGO, ILLINOIS.

GAME TABLE.

Application filed October 28, 1925, Serial No. 65,816. Renewed November 5, 1928.

My invention relates particularly to pool and billiard tables although not limited to this use alone.

The main features of the invention reside 5 in the provision of a bed supporting structure which provides a light, solid and effective adjustable support for the bed of the table with a view toward economy in manufacture and assembly.

10 The invention relates particularly to a metal table construction and certain features of the invention relate to the construction of a metal table with the aforementioned features in view.

15 With these features in view my invention consists in certain features of novelty in the construction, combination, and arrangement of parts by which the said features and certain other features, hereinafter appearing, 20 are effected, all as fully described with reference to the accompanying drawings and more particularly pointed out in the claims.

In the said drawings—

Figure 1 is a top plan view of a game table 25 frame and bed mounted thereon and partially broken away.

Figure 2 is a section on the line 2—2 of Fig. 1.

Figure 3 is a partial sectional view on the 30 line 3—3 of Fig. 1.

Figure 4 is an enlarged partial section on the line 4—4 of Fig. 1 intermediately broken away and condensed.

Like characters of reference indicate like 35 parts in the several views.

Referring to the drawings 1 designates an elongated rectangular sheet metal, such as sheet steel, frame of deep sided marginal formation, and this frame is supported on 40 sheet metal legs 2 at the corners of the frame as is usual. The frame is provided with an outwardly projecting upwardly disposed horizontal portion 3 extending therearound and with a vertical upwardly extending 45 flange 4 at the outer edge of the horizontal portion and extending therearound. Inverted U-shaped sheet metal, such as sheet steel, supports 5 extend across between the long sides of the frame in spaced relation with 50 the ends of the frame and each other and are permanently secured to the long sides of the table, such as by riveting, and have the upper surfaces thereof disposed in the plane of the upper surface of the horizontal portion 3 of 55 the frame.

Metal right angle bars 6 at the top of the frame extend longitudinally thereof between the long sides of the frame in spaced parallelism with each other and with the long sides of the frame and have legs thereof disposed in a horizontal plane and overlying the horizontal portion 3 of the frame and the supports 5 and secured thereto. The other legs of these angle bars 6 project vertically upwardly from the aforementioned legs thereof, and a plurality of metal bed supporting bars 7 are arranged in aligned sets along respective of the vertical flanges 4 of the long sides of the frame and the vertical legs of the angle bars 6. These bars 7 are secured in vertically adjusted positions facewise against vertical faces of the flanges 4 or the vertical legs of the angle bars 6 as the case may be by means of horizontally disposed headed screws 8 spaced along these bars and extending through vertically elongated apertures 9 in the bars 7 and apertures in the vertical legs of the angle bars or the flanges 4 and nuts 11 screwthreaded on said screws and clamping the bars 7 facewise against the vertical faces of the vertical legs of the angle bars 6 or the flanges 4, the vertically elongated apertures 9 permitting vertical adjustment of the bars 7. See Figs. 1 and 4.

A pair of screws 8 and nuts 11 are provided 85 for securing each bar 7 and they are disposed adjacent respective ends of each of these bars.

Vertically disposed adjusting screws 12 are screw-threaded through the horizontal portions 3 at the long sides of the table and through horizontal plates 13 secured on the horizontal legs of the angle bars 6 and are spaced along the bars 7 and are adapted to abut the lower surface of respective of these bars 7 for vertically adjusting the same, two of these screws 12 being provided for each bar 7 and being disposed adjacent respective ends thereof. Thus the bars 7 may be vertically adjusted by manipulation of the 90 screws 12 while the screws 8 and nuts 11 are not fully tightened, and after the adjustment is made the screws 8 and nuts 11 are fully tightened to secure these bars in their vertically adjusted positions.

The bars 7 constitute the sole support for the slate bed 14 of the table, and are arranged in parallel sets of aligned bars extending longitudinally of the table. As shown the bed comprises, as is usual, three sections arranged 110

edgewise longitudinally of the frame and said sets. Each bar 7 of each set thereof engages a respective section of the bed so that each section of the bed may be adjusted independently in order to position the upper surfaces of the sections of the bed in a common plane.

The upper face of the bed is finished as is usual, and a plurality of grooves 15 are cut 10 into the lower face thereof and extend longitudinally of the bed in spaced parallelism corresponding with the aligned sets of bars 7 and form finished surfaces disposed in a common plane parallel with the upper face of the bed 15 and adapted to engage respective of the sets of bars 7 when the bed is seated thereon.

Certain features of the bed supporting structure described herein are described and claimed in my co-pending application Serial 20 No. 687,035, filed January 18, 1924, for improvement in game table, patented January 5, 1926, No. 1,568,166.

The marginal structure of the bed shown requires no description for the present purposes, and is fully described and claimed in my U. S. Letters Patent No. 1,516,654, dated November 25, 1924, for improvement in game table.

In the use of the term slate I do not wish my 30 invention specifically limited thereto as the invention is adapted for other materials as well, but have used the term for the reason that slate is the material of which game table beds are universally made at the present 35 time.

While I have herein shown and particularly described the preferred embodiment of my invention I do not wish to be limited to the precise details of construction shown as 40 changes may readily be made without departing from the spirit of my invention, but having thus described my invention I claim as new and desire to secure by Letters Patent the following:

45 1. The combination with a metal game table frame, of a plurality of horizontally extending metal formations fixed therewith and all extending in the same direction in spaced relation, a plurality of metal bed-supporting members arranged in sets of aligned members along respective horizontally extending formations, and means whereby said supporting members are mounted on respective formations for vertical adjustment.

55 2. The combination with a metal game table frame of elongated rectangular marginal formation, of horizontally extending metal frame members fixed therewith and extending longitudinally of the frame in parallelism and provided with vertical faces, a plurality of metal bed-supporting bars arranged in sets along respective frame members, and means whereby said bars are secured facewise against the vertical faces of

respective frame members in independent 65 vertically adjusted positions.

3. The combination with an elongated rectangular sheet metal game table frame of deep sided marginal formation and having the upper edge portions of the long sides 70 thereof arranged vertically, of horizontally extending metal frame members at the top of the frame and fixed therewith and extending longitudinally thereof between said long sides in parallelism with each other and with 75 said sides, a plurality of metal bed-supporting bars arranged in aligned sets along respective of said upper edge portions and said frame members, and means whereby said bed-supporting bars are secured facewise 80 against vertical faces of respective of said upper edge portions and said frame members in independent vertically adjusted positions.

4. The combination with an elongated rectangular sheet metal game table frame of 85 deep sided marginal formation provided with an upwardly disposed outwardly projecting horizontal portion extending therearound and with a vertical flange at the outer edge of the horizontal portion and extending 90 therearound, metal right angle bars at the top of the frame and extending longitudinally thereof between the long sides of the frame in spaced parallelism with each other and with said sides and having legs thereof 95 overlying said horizontal portion of the frame and secured thereto, and having the other legs thereof projecting vertically upwardly therefrom, transverse metal supports extending across between and secured to the 100 long sides of the frame and underlying and secured to said angle bars, a plurality of metal bed-supporting bars arranged in aligned sets along respective of the vertical flanges of the long sides of the frame and said angle bars, and screws passing through apertures in respective of the flanges of the long sides of the frame and the vertical legs of 105 said angle bars and the bed-supporting bars for securing the bed supporting bars, facewise against vertical faces of respective of the vertical flanges of the long sides of the frame and the vertical legs of said angle bars, in independent vertically adjusted positions.

5. The combination with a game table 115 frame, of a horizontally extending formation fixed with the frame and provided with a vertical face, a horizontally disposed bed-supporting member arranged along said formation, means including horizontally disposed screws spaced along said bed-supporting member for securing the same in vertically adjusted position against said vertical face, and means including vertically disposed screws spaced along said bed-supporting member for vertically adjusting said bed-supporting member.

6. The combination with a metal game

- table frame, of a horizontally extending metal formation fixed with the frame and disposed in a vertical plane, a horizontally disposed metal bed-supporting bar arranged 5 along said formation, means including horizontally disposed headed screws spaced along said bar and extending through apertures in said formation and bar and nuts screwthreaded on said screws for securing 10 the bar facewise against a vertical face of said formation in vertically adjusted position, and means including vertically disposed screws spaced along said bar for vertically adjusting said bar.
- 15 7. The combination with a metal game table frame, of a horizontally extending metal formation fixed with the frame and disposed in a vertical plane, a horizontally disposed metal bed-supporting bar arranged 20 along said formation, means including horizontally disposed headed screws spaced along said bar and extending through vertically elongated apertures in the bar and apertures in said formation and nuts screwthreaded on said screws for securing the bar facewise against a vertical face of said formation in vertically adjusted position, and means including vertically disposed screws 25 spaced along said bar and adapted to abut the lower surface of said bar for vertically adjusting said bar.
- 30 8. The combination with a game table
- frame, of a plurality of horizontally disposed bed-supporting members and all extending in the same direction and constituting the sole support for the bed of the table, means including horizontally disposed screws spaced along said supporting members for securing the same in independent vertically adjusted positions, and means including vertically disposed screws spaced 35 along said supporting members for vertically adjusting the same.
9. The combination with a metal game table frame, of a plurality of parallel horizontally disposed metal frame formations fixed therewith and disposed in vertical planes, a plurality of metal bed-supporting bars arranged in sets along respective frame formations, means including horizontally 40 disposed headed screws spaced along said bars and extending through vertically elongated apertures in the bars and apertures in said formations and nuts screwthreaded on said screws for securing the bars facewise 45 against vertical faces of said formations, and means including vertically disposed screws spaced along said bars and adapted to abut the lower surfaces of said bars for vertically 50 adjusting the same.
- 55

In witness whereof I hereunto affix my signature this twenty-first of October, 1925.

THEODORE R. TREIBER.
